UNITED STATES PATENT OFFICE.

JOHN M. BIDDLE, OF CHICAGO, ILLINOIS, ASSIGNOR TO UNION SPECIAL MACHINE COMPANY, OF CHICAGO, ILLINOIS, A CORPORATION OF ILLINOIS.

LOOPER SUPPORT FOR SEWING MACHINES.

Application filed May 15, 1926. Serial No. 109,343.

The invention relates to new and useful improvements in looper supports for sewing machines, and more particularly to means for supporting a thread carrying looper.

5 An object of the invention is to provide a looper support which is so constructed that the looper may be stamped from metal, so far as the construction of the shank of the looper is concerned, and yet have a durable clamping support in the carrier on which it is mounted.

10 A further object of the invention is to provide a looper of the above type which is so constructed that a plurality of loopers 15 may be secured to the carrier therefor by a single clamping nut, and wherein said loopers may be independently adjusted on the carrier in a direction transversely of the longitudinal axis of the carrier.

20 A further object of the invention is to provide a looper which is so constructed that it may be readily mounted directly on a crank carried by the operating shaft without the use of any set screws or the like engaging 25 the shank of the looper.

These and other objects will in part be obvious and will in part be hereinafter more fully disclosed.

30 In the drawings which show by way of illustration one embodiment of the invention—

Figure 1 is an end view of a looper support embodying the improvements;

Fig. 2 is a plan view of the same;

35 Fig. 3 is a sectional view on the line 3—3 of Fig. 1;

Fig. 4 is a sectional view on the line 4—4 of Fig. 2;

40 Fig. 5 is a sectional view on the line 5—5 of Fig. 2.

Fig. 6 is a view similar to Fig. 2, but showing a modified form of looper and supporting means therefor;

45 Fig. 7 is a sectional view on the line 7—7 of Fig. 6, and

Fig. 8 is a view similar to Fig. 6, but showing a modified form of looper and looper support.

50 The improved looper and support therefor consists broadly of a looper and carrier which are so constructed as to have substantially flat parallel engaging surfaces so that the looper is held from rotation on the carrier, and at the same time, permitted to move longitudinally of the carrier, whereby a

single looper or a plurality of loopers may be clamped on the carrier by a single clamping nut. In one form of the invention, the shank of the looper is forked, while in the other form of the invention, the shank of the 60 looper is made of a single member. In both cases, however, the side faces of the shank are flat and parallel, and the entire looper is of such construction that it may be stamped from metal. The looper carrier, in the 65 preferred form of the invention, is slabbed so as to form a central portion with parallel flat faces, and this central portion is adapted to be straddled by the forked members of the looper shank, and the flat faces of the 70 looper and the carrier thus brought into engagement with each other so that the looper is held from rotating on the carrier. In the other form of the invention, the looper carrier has a recess centrally therethrough, 75 thus forming parallel flat faces which are adapted to engage the flat faces on the single member of the shank of the looper, and thus it is again that the looper is held from rotating on the looper carrier. These slabbed 80 sides of the looper carrier and this central recess in the looper carrier are of sufficient length so that when the loopers are mounted on the carrier, the looper may move longitudinally of the carrier. In certain forms of the invention, a series of 85 loopers may be used and the loopers spaced from each other by spacing collars or by an extra thickness in the shank which engages the carrier, and the looper or the loopers, 90 when a plurality of loopers are used, are all forced by a single nut against an abutment or shoulder on the carrier and thus clamped to the looper carrier. This carrier is preferably in the form of a crank mounted 95 directly on the end of the looper shaft, and the looper shaft is oscillated so as to move the looper or the loopers into and out of their respective needle thread loops.

I will describe in detail first, the preferred form of the looper, wherein the shank of the looper is forked, and I will then describe the other modified forms.

In all forms of the invention, the looper consists of a looper body 1 which is provided with the usual eye at the point thereof and at the heel with a connecting groove along the side face of the looper. The looper is formed with an integral shank portion 2 which is flat. The entire looper can 110

be stamped from sheet metal. In the preferred form of the invention, this flat shank portion 2 is provided with spaced arms 3 and 4, thus forming a forked shank which 5 is open at its lower end. The operating shaft is indicated at 5. Mounted on this shaft is a head 6. The head 6 is clamped to the shaft 5 by means of a locking pin 7. This locking pin 7 is provided with a segmental recess 8 which is curved to conform 10 to the curvature of the shaft 5. The recess is placed in proper alinement with the opening in the head 6 through which the shaft 5 passes. This pin 7 is threaded as indicated 15 at 9, and a nut 10 turned on to the threaded end of the pin, engages the side face of the head 6, and when turned down against said side face, will cause the wall of the segmental recess 8 to grip the shaft 5 and thus 20 firmly lock the head on the shaft. This head 6 is provided with a carrier 11 for the looper or loopers, and this carrier is in the form of a crank which is offset from the central longitudinal axis of the shaft 5. The carrier 25 11 is provided with flat faces 12 and 13 (see Fig. 5) which are parallel with each other. The members 3 and 4 are spaced so that the shank of the looper may be placed over the carrier 11, and these members 3 and 4 will 30 engage the side faces of the carrier.

In Fig. 3 of the drawings, two loopers 1 and 1^a are shown as mounted on the carrier. The looper 1 is placed on the carrier, and the side face of the shank is moved up into contact with the shoulder 14. Next on the carrier, is placed a collar 15, and then the looper 1^a. When the carrier is made sufficiently long for more loopers than shown in Fig. 3, a clamping sleeve 16 is used. Both the 40 collar 15 and the sleeve 16 have their inner recesses of the same diameter as the maximum diameter of the carrier 11. The end of the carrier is threaded at 17, and a nut 18 is screwed thereon. This nut engages the 45 sleeve 16 and forces the sleeve against the looper 1^a, the looper 1^a against the collar 15, the collar 15 against the looper 1, and the looper 1 against the shoulder 14. Thus it is 50 that the loopers are firmly clamped on the carrier 11. Inasmuch as the shanks of the loopers are forked and engage the flat faces of the carrier, these loopers cannot oscillate on the carrier, but are oscillated with the carrier when the operating shaft 5 is oscillated. By loosening the nut 18, the 55 loopers can be adjusted bodily in a direction transversely of the longitudinal axis of the carrier. This adjustment of one looper can be made independently of the adjustment of 60 the other looper, and thus the point of the looper relative to the axis of the operating shaft can be varied. The looper is curved substantially about the axis of the operating shaft. As noted above, more than two 65 loopers may be used, and these loopers may

be constructed so that the points are set to pass the needles at slightly different intervals. The looper carrier may be shortened if desired, from that shown in the drawings, in which case, the clamping sleeve 70 16 should be omitted.

In the form of the invention shown in Figures 6 and 7, the shank portion 2 of the looper is provided with a single supporting member 19 instead of spaced arms forming 75 a fork. The carrier 11 is circular in cross section throughout its entire extent, and is provided with an elongated rectangular recess 20 which extends all the way through the carrier. This recess 20 forms parallel 80 flat faces which are adapted to engage the flat faces on the shank member 19 of the looper. Thus it is that the looper is held from oscillating or rotating on the looper carrier. The shank member 19 as shown in 85 Fig. 6 of the drawings is made considerably thicker than the body portion of the looper, and this thickened portion of the shank indicated at 21 in Fig. 6 of the drawings, takes the place of the spacing collar 15. When 90 a plurality of loopers are used they are placed in the slot 20 side by side. This slot extends clear up to the abutment or shoulder 14 on the looper carrier, so that when the nut 18 is turned on to the threaded 95 portion 17 of the carrier, it will force one looper against the other and the inner looper against the abutment or shoulder 14, and thus it is that the loopers will be firmly clamped on the carrier. The loopers may be 100 adjusted after the same manner described above in connection with the forked shank. In Fig. 8 of the drawings, the loopers are similar in construction to those shown in Figures 6 and 7, except the thickened portion 21 on the shank member of the looper is omitted, and spacing collars indicated at 105 15 are used.

It is obvious that minor changes in the details of construction and the arrangement 110 of the parts may be made without departing from the spirit of the invention as set forth in the appended claims.

Having thus described the invention, what I claim as new and desire to secure by Letters Patent, is—

1. A looper support for sewing machines comprising a carrier having a non-circular cross section, a looper having a forked shank adapted to straddle said carrier, said carrier having a shoulder at one end thereof and a clamping nut at the other end thereof for forcing the looper against said shoulder for clamping the same to the carrier. 120
2. A looper support for sewing machines comprising a looper carrier, an operating shaft, a head mounted on the end of said shaft, said looper carrier being connected to said head and located at one side of the center of the operating shaft, said carrier 13

being irregular in cross section, a looper mounted on the carrier having a forked shank adapted to straddle the carrier and conform to the irregular cross section of the carrier so as to be held from oscillation on the carrier, said carrier having a shoulder at one end thereof and a clamping member at the other end thereof adapted to clamp said looper shank against the shoulder and thus lock the looper to the carrier.

3. A looper support for sewing machines comprising a carrier having flat opposed faces, a looper having a flat shank provided with a forked end forming spaced members disposed so as to engage said flat faces of the carrier when the shank of the looper is placed on the carrier, said carrier having a shoulder at one end thereof and a clamping member at the other end thereof adapted to hold said shank of the looper clamped against said shoulder.

4. A looper support for sewing machines comprising an operating shaft, a head secured to said operating shaft, a projecting carrier formed integral with said head and offset from the center of said shaft, said carrier having opposed flat faces, a series of loopers, each of which is provided with a flat shank having a forked portion adapted to straddle the carrier and engage the flat faces thereof, spacing collars between the loopers, said carrier having a shoulder at one end thereof, and clamping means for clamping the loopers and collars against said shoulder.

5. A looper support for sewing machines comprising an operating shaft, a head secured to said operating shaft, a projecting carrier formed integral with said head and offset from the center of said shaft, said carrier having opposed flat faces, a series of loopers, each of which is provided with a flat shank having a forked portion adapted to straddle the carrier and engage the flat faces thereof, spacing collars between the

loopers, said carrier having a shoulder at one end thereof, and clamping means for clamping the loopers and collars against said shoulder, said head having a passage therethrough for said shaft and a passage 50 therethrough for the clamping pin, which last-named passage intersects the first-named passage, a pin located in the last-named passage and having a segmental recess to receive the shaft, said pin extending outside of said 55 head and adapted to receive a nut whereby the pin may be caused to grip the shaft and lock the head on the shaft.

6. A looper support for sewing machines comprising an operating shaft, a head having a passage therethrough for the shaft, said head having a second passage at right angles to the passage for the shaft and intersecting the same, a pin located in said second passage and having a recess adapted to receive the shaft when the head is placed on the end of the shaft, said pin projecting beyond the side face of the head and threaded to receive a nut whereby the pin may be moved endwise for gripping the shaft and locking the head thereto, a looper carrier mounted on said head at one side of the axis of the shaft, and means for clamping the looper on said carrier whereby said looper is located in a plane disposed at right angles 70 to the longitudinal axis of the operating shaft.

7. A looper support for sewing machines comprising a carrier having a shoulder at one end thereof and a clamping nut at the 80 other end thereof, a looper supported on said carrier between said nut and said shoulder and adapted to be clamped against the shoulder by said nut, said carrier and looper having interengaging means whereby said 85 looper is free to move endwise of the carrier and is held from turning on said carrier.

In testimony whereof, I affix my signature.

JOHN M. BIDDLE.
